His ATTORNEY

UNITED STATES PATENT OFFICE.

WILLIAM ARTHUR COLLINGS, OF KANSAS CITY, MISSOURI.

REINFORCEMENT FOR CONCRETE COLUMNS.

1,274,687.

Specification of Letters Patent. Patented Aug. 6, 1918.

Application filed August 13, 1917. Serial No. 185,876.

To all whom it may concern:

Be it known that I, WILLIAM ARTHUR COLLINGS, a citizen of the United States, residing at Kansas City, in the county of Jackson and State of Missouri, have invented a certain new and useful Improvement in Reinforcements for Concrete Columns, of which the following is a specification.

My invention relates to improvements in 10 reinforcements for concrete columns.

It relates particularly to metal reinforcements which employ an upright wire spiral, the coils of which are engaged by upright reinforcing spacing bars.

15 The object of my invention is to provide a reinforcement of the kind described, which is economical to manufacture, which has great strength, which may be readily molded in a column of concrete, and which may be 20 quickly collapsed to compact form for storage and shipment.

The novel features of my invention are hereinafter fully described and claimed.

In the accompanying drawing, which 25 illustrates my invention,

Figure 1 is a side elevation of a portion of a concrete column provided with the preferred embodiment of my invention.

Fig. 2 is a top view of the reinforcement 30 shown in Fig. 1.

Fig. 3 is a side elevation, partly broken away, of a portion of the reinforcing means shown in Fig. 1, enlarged.

Fig. 4 is a cross section on the line 4—4 35 of Fig. 3.

Fig. 5 is a side elevation of the reinforcing means shown in Fig. 1, shown collapsed.

Fig. 6 is a side elevation, partly broken away, showing a modification of my invention. 40

Fig. 7 is a cross section on the line 7—7 of Fig. 6.

Fig. 8 is a top view, partly in horizontal section, of another modified form of my invention. 45

Similar reference characters designate similar parts in the different views.

1 designates an upright wire spiral, the coils of which are, preferably, inclined 50 slightly to the horizontal.

A plurality of upright reinforcing means are preferably employed for spacing the coils of the spiral at different points.

Each reinforcing means is, preferably, 55 T-shaped in cross section, and as they are alike, a description of one will suffice for

each of the reinforcing means shown in Figs. 1 to 5.

2 and 3 designate respectively two upright flat bars disposed at right angles to each other, the bar 2 forming the stem of the T and the bar 3 the head thereof.

The bar 2 is provided, preferably, in the edge adjacent to the bar 3 with a plurality of openings or notches 4 in which the coils 1 of the spiral are preferably pivotally mounted.

A plurality of securing devices 5 consisting preferably of short pieces of wire embracing the inner edge and opposite sides of the bar 2 and extend through openings provided therefor in the bar 3, the ends of each securing device 5 being secured to the outer side of the bar 3, preferably by being bent parallel therewith.

75 The securing devices 5 preferably respectively embrace the upper and lower sides of the coils 1, thereby holding the bars 2 and 3 against longitudinal movement relatively to each other.

By sliding the reinforcing means to opposite sides of the spiral, the latter may be collapsed, as shown in Fig. 5.

When the spiral is disposed in the operative position, shown in Fig. 1 the reinforcement 85 may be readily molded in concrete 6.

By disposing the bars 2 and 3 at right angles to each other, with the bar 3 at the outer side of the spiral, and the bar 2 disposed radially with respect to the spiral, 90 great rigidity and strength is afforded to the reinforcement.

In the form of my invention shown in Figs. 6 and 7, a reinforcing bar 2, similar to that shown in Fig. 1 is employed. In lieu 95 of the bar 3, I provide an upright flat bar 7, disposed at right angles to the bar 2, so as to form, in cross section, a T. The inner side of the bar 7 is provided with a plurality of transverse grooves 8, which are disposed respectively in register with the openings or notches 4 so as to receive therein the wire securing devices 5, which engage the bars 2 and 7 and coils 1, as described with reference to the securing devices 5 employed in 105 the form shown in Fig. 1.

The mode of operation of the form shown in Figs. 6 and 7 is the same as that shown in the preceding figures.

In the form of my invention shown in 110 Fig. 8, the construction is the same as that shown in Figs. 1 to 5, with the exception

that there is substituted for the vertical spacing bar 3, an upright spacing bar 9 which is disposed at right angles to the bar 2, so as to form in cross section a T. The 5 bar 9 has punched from its opposite vertical edges respectively, a plurality of inwardly extending tongues 10, which respectively embrace opposite sides of the bar 2, thereby firmly holding the latter from lateral movement relatively to the bar 9. The 10 securing devices 5 are extended through the openings provided in the bar 9 in the formation of the tongues 10 and, as in the form shown in Fig. 1, the securing devices 15 respectively embrace the upper and lower sides of the coils 1, and have their outer ends bent parallel with and disposed against the outer side of the spacing bar 9.

I do not limit my invention to the structures shown and described, as various modifications, within the scope of the appended claims, may be made without departing from the spirit of my invention.

What I claim is:—

- 25 1. A reinforcement for concrete columns comprising an upright wire spiral, two upright bars disposed at right angles to each other, one of the bars having openings through which the coils of the spiral respectively extend, and securing devices 30 respectively intermediate of said coils and embracing one edge and two sides of the bar having said openings and extending through and secured to the other bar.
- 35 2. A reinforcement for concrete columns comprising an upright wire spiral, two upright bars disposed at right angles to each other, one of the bars having openings 40 through which the coils of the spiral respectively extend, and securing devices respectively embracing said coils and one edge and two sides of the bar having said openings and extending through and secured to the other bar.
- 45 3. A reinforcement for concrete columns comprising a collapsible upright wire spiral, two upright bars disposed at right angles to each other, one of the bars having openings 50 in which the coils of the spiral are respectively pivotally mounted, and reinforcing

devices respectively intermediate of said coils and embracing one edge and two sides of the bar having said openings and extending through and secured to the other bar.

4. A reinforcement for concrete columns 55 comprising a collapsible upright wire spiral, two upright bars disposed at right angles to each other, one of the bars having openings in which the coils of the spiral are respectively pivotally mounted, and reinforcing devices respectively embracing said coils and one edge and two sides of the bar having said openings and extending through and secured to the other bar.

5. A reinforcement for concrete columns 60 comprising an upright wire spiral, two upright bars, one having notches in one edge which respectively contain the coils of the spiral, the other bar extending across said notches and closing the same, and means for 70 securing said bars together and for holding them against relative longitudinal movement.

6. A reinforcement for concrete columns 75 comprising an upright wire spiral, two upright bars, each having notches coöperating with the notches in the other bar for holding the coils of the spiral, and means for securing the bars together.

7. A reinforcement for concrete columns 80 comprising an upright wire spiral, two upright bars, one of the bars being disposed edgewise to the flat side of the other bar, said other bar having transverse grooves coöperating with edge grooves provided in the 85 opposite bar for receiving the coils of the spiral, and means for securing said bars together.

8. A reinforcement for concrete columns 90 comprising an upright wire spiral, two upright bars, one having an edge disposed against the flat side of the other, said edge having notches coöperating with transverse grooves in the opposite bar for receiving the coils of the spiral, and securing devices 95 each embracing one of the coils and both of said bars for holding the bars together.

In testimony whereof I have signed my name to this specification.

WILLIAM ARTHUR COLLINGS.
